FIG. 5.

UNITED STATES PATENT OFFICE.

EUGENE L. HORTON, OF SAN FRANCISCO, CALIFORNIA.

AUTOMATIC AIR-COUPING.

1,386,338.

Specification of Letters Patent. Patented Aug. 2, 1921.

Application filed January 14, 1920. Serial No. 351,453.

To all whom it may concern:

Be it known that I, EUGENE L. HORTON, a citizen of the United States, residing at city and county of San Francisco and State of California, have invented new and useful Improvements in Automatic Air-Couplings, of which the following is a specification.

This invention relates to a train coupler.

It is the principal object of the present invention to provide automatic means whereby the air, steam, and electric conduits of railway cars may be simultaneously and automatically coupled, coincident with the coupling of the car draw bars.

15 The present invention contemplates the use of a pair of coupling heads carrying the terminals of the various conduits of a car and provided with interlocking means whereby they may be secured in abutting relation to each other, and communication established between the respective conduits without possibility of leakage, even though the cars negotiate a sharp curve along the right of way.

25 The invention is illustrated by way of example in the accompanying drawings, in which:

Figure 1 is a fragmentary view in side elevation, showing the draw bar connections between two railway cars and further disclosing the automatic couplings with which the present invention is concerned.

30 Fig. 2 is a view in plan, illustrating the adjacent ends of two railway cars and showing the details of construction of the couplers.

35 Fig. 3 is an enlarged sectional view in plan showing the coupler heads with which the present invention is concerned.

40 Fig. 4 is a view in end elevation showing the arrangement of one of the heads.

Fig. 5 is a fragmentary view in side elevation showing a simplified form of the present invention as used upon freight

45 trains.

Fig. 6 is a view in end elevation showing the automatic coupler head.

Fig. 7 is a fragmentary view in plan showing the manner in which the air valve

50 may be operated from either side of the train.

Referring more particularly to the drawings, 10 and 11 indicate two railway cars adapted to be connected to each other by

55 means of draw bars 13. These draw bars are fitted with complementary coupling

heads 14, having coupling pins 15 by which the heads may be secured together. These pins may be raised and lowered by levers 16 mounted upon the bolsters of the cars. 60 It will be understood that the coupling head construction may be of any desired design, and that the present invention is more particularly concerned with means whereby the train lines may be automatically connected. 65 This is accomplished by the use of automatic coupling heads 18 and 19 which are positioned beneath the main draw bar heads 14 as clearly shown in Fig. 1. These coupling heads are supported upon hangers 20 70 which have vertical shanks extending upwardly through brackets 21 on the railway cars. The upper ends of the shanks are fitted with nuts 22. Interposed between the brackets 21 and the nuts are compression 75 springs 23 by which the hangers 20 are yieldably supported. In view of the fact that the automatic coupling heads are intended to swing laterally, the lower supporting portion 24 of each of hangers 20 is formed on 80 an arc while lying flat in a horizontal plane. Radius rods 20' are pivoted to the hangers 20 near their lower ends and also pivoted to the body of the car so that the hangers will be steady in their movement and will 85 thus provide a stable support for the coupling heads.

Referring more particularly to Fig. 4, it will be seen that the automatic coupler head 20 is rectangular in section and that it 90 is formed with an air signal opening 25, air break opening 26, and a steam opening 27.

The openings are fitted with packing gaskets 30 which are seated within counter bores in the vertical end face of each of 95 the automatic coupler heads and project therefrom so that when in register, they will forcibly engage each other and prevent leakage of the fluid passing from one head to the other. The opening 25 is in communication with an air line signal 31, while the opening 26 is in communication with an air break line 32. A steam hose is led to the opening 27. Interposed at a point in the air line and the steam line are two-way 100 valves 34 and 35, respectively. These valves are incorporated within a T-valve casing construction so that it will be possible to position hose connections upon the extensions of said T so that the cars may be used, 105 even though the cars to which they are coupled are not equipped with the automatic

coupling head. The main cut off valve 36 is fitted upon each of the train lines and may be operated by suitable shifting mechanism secured beneath the frame of the car 5 and adapted to be operated from both sides thereof.

The connections between the train line and the coupling heads are flexible, thus permitting the heads to move laterally in a 10 horizontal plane and at the same time to move longitudinally of the car.

For this reason, the coupling heads 18 and 19 are each fitted with a horizontal shank 37 which extends through brackets 15 38 and 39, and may reciprocate horizontally as caused by relative changes in position between the two cars. The shanks are pivoted to the coupling heads by vertical pivot pins 20 40 which allow horizontal swinging movement from the axis of the pins while insuring that horizontal reciprocation of the shanks 37 may take place. A helical spring 41 is disposed around each of the shanks 37 and interposed between the bearing 38 25 and a pivot extension on the rear of the head, thus permitting yieldable movement of the head relative to the shank and insuring that the head will be restored to its original position after the spring has been 30 compressed, either due to longitudinal movement of the head or swinging movement thereof.

In order that the gaskets 30 upon opposing coupling heads will register and produce a tight joint, guide fingers 43 are secured to the ends of the adjacent coupling heads and project forwardly from the end face thereof as clearly shown in Fig. 3. These fingers are slightly curved so that 40 they will have no trouble in finding a seat along the sides of the heads. This seat is here shown as in the form of a groove 44, one of which is secured in one side face of each of the heads, the grooves upon the two heads 45 being disposed upon opposite sides of the heads in relation to each other. Centering arms 45 are secured upon the same sides of the heads as the grooves 44, and are flared outwardly in order to catch the ends of 50 the guide fingers and swing the heads so that the guide fingers will properly seat at the opposite sides of the heads, and at the same time cause the abutting ends of the two heads to properly register with each 55 other and form continuations of the conduits across the heads and through the gaskets. Lock openings 46 are formed through the arms 45 at points near their base and are intended to receive the projecting ends of 60 the lock fingers 43, so that the fingers will be frictionally held and the two abutting coupler heads held rigidly together until the frictional engagement is broken, due to 65 the complete disengagement of one car from the other.

Referring to Figs. 5, 6 and 7, inclusive, an adaptation of the present invention for use on freight cars will be seen. In this instance the air coupling heads 18 and 19 are only formed with the opening 26 which is 70 connected with an air brake hose 32. This head is formed in the manner previously described, having the extending portions 43 and 45 adapted to interlock and to hold the faces of the two heads in intimate contact 75 with each other. A T valve 50 is interposed at a point in the train line and is equipped with a separate length of hose 51 which may be used when the car connected therewith is 80 not equipped with the automatic air coupling. This will insure that all cars will be properly coupled even though all of the rolling stock has not been overhauled, embodying the present invention. A cut off valve 52 is shown in the end of the train line and 85 controlling the flow of air to the hose 32. This valve may be operated from either side of the train by means of the shifting mechanism shown in Fig. 7. This mechanism comprises a shifting rod 52 sliding through bearings 53 and 54 as operated by handles 55. A bell crank lever 56 is pivoted beneath the cross beam of the car and is pivotably connected by one arm to the shift rod as indicated at 57. The opposite end of this lever is fitted with a connecting rod 58 secured to the lever 59 of the valve stem. In this manner the valve stem may be easily rotated by the manipulation of either of the handles 55. The operation of the simplified form of the invention is identical with that of the more complicated form as shown in 90 Figs. 1 to 4, inclusive and which operation 95 will be hereinafter set forth.

In operation of the present invention, the 100 device is assembled as particularly shown in Fig. 1, and when two cars are coupled together by means of the draw bars 13 and the coupling heads 14, the automatic coupling heads 18 and 19 will be drawn together as 105 these last named heads move toward each other. The fingers 43 will overlap the sides of the heads and will encounter the guide arms 45. After the two heads continue to move to positions against each other, the 110 guide arms will properly adjust the fingers and cause the ends of the heads to coincide and come to a locked position. In the event that one of the cars is more heavily loaded than the other, it will be seen that the two 115 coupled heads 18 and 19 will be out of horizontal alinement. This will be taken care of, however, by means of the fingers 43 which have tapered upper and lower sides 120 as shown in Fig. 4, and which sides will cooperate with the upper and lower faces of the grooves 44 to bring the coupling heads in proper alinement with each other even though they, themselves, are out of horizontal alinement. As the coupling heads 125 130

are swung, the hangers will be moved up and down as permitted by the springs 23. After the two heads have been locked together due partially to the locking of the draw bars, 5 and partially to the frictional engagement with the arms 45, the two cars may have considerable lateral movement in relation to each other. It will further be evident that longitudinal movement may be had by the 10 compression and expansion of springs 41.

It will thus be seen that the coupling structure here disclosed, while simple in its construction, has provided automatic means whereby the various train lines may be instantaneously connected and maintained in their joint condition without danger of leakage, even though the cars assume various positions in relation to each other due to the curve of the trackway or differences in the 15 design and loading of the cars, and it will be further observed that the construction embodies a mechanism which is not liable to require repair and will be positive in operation at all times.

25 While I have shown the preferred form of my invention as now known to me, it will be understood that various changes in the combination, construction, and arrangement of parts may be made by those skilled in the 30 art without departing from the spirit of the invention as claimed.

Having thus described my invention, what I claim and desire to secure by Letters Patent is:

35 1. In an air and like coupling of the character described, flat abutting heads with connecting fluid passages, hangers suspended from the car and having the lower ends lying horizontally, curved into arcs and 40 serving to support the coupling heads and allow for horizontal adjustment, and spring means in conjunction with said hangers to permit vertical adjustment of the heads while supported thereby.

45 2. In an air coupling of the character described, a pair of horizontally disposed coupling head members having flat abutting ends in a plane substantially at right angles to the longitudinal axes of said heads with 50 connecting fluid passages, hangers by which the coupling heads are supported, a tapered guide finger formed on each head, said fingers being outwardly flared and formed upon opposite sides of the heads, and 55 said coupling heads having complementary grooves for receiving the guide fingers, and means associated with said grooves whereby the fingers will be frictionally held when the abutting ends of said coupling heads are 60 brought together.

65 3. In an air coupling of the character described, a pair of horizontally disposed coupling head members having flat abutting ends with connecting fluid passages, hangers by which the coupling heads are

supported, a tapered guide finger formed on each head, said fingers being outwardly flared and formed upon opposite sides of the heads, and said coupling heads having complementary grooves for receiving the guide fingers, a guide arm extending outwardly over each groove and each arm having an opening adjacent the inner end of the groove with which it is associated, adapted to receive and frictionally hold the outer end of 70 a guide finger when the abutting ends of said coupling heads are brought together.

4. An air coupler comprising in combination with a draw bar coupling head, a secondary coupling head disposed beneath said first-named head, means for permitting said secondary head to have universal movement and mounted upon the bottom of a railway car, a plurality of terminal openings in the 80 vertical end face of said head, a guide finger projected from one side of said face, a guide groove recessed in the opposite side of the head from the finger, a guide arm extending outwardly over said groove for receiving a 85 guide finger of a complementary head, and means for interlocking said fingers and arms upon abutting heads whereby they will be held in fixed relation to each other.

5. An automatic air coupler, comprising a draw bar, a coupling head carried thereby, a 95 hanger yieldably supported from the railway car and forming a horizontal loop beneath the draw bar head, a secondary coupling head supported by said looped portion, a plurality of vertically aligned conduit terminals formed in the vertical end face of 100 said secondary head, and in communication with separate train lines, means for yieldably supporting said head for universal swinging movement and longitudinal movement, and combined guide and locking means carried upon said second head, whereby the disposition of the draw bar heads in locked 105 relation to each other will cause the end faces of complementary secondary heads to be locked in abutting relation to each other and various conduit terminals held in register.

6. An automatic air coupler, comprising in combination with a draw bar coupling 115 head of a secondary coupling head disposed beneath said draw bar, an arc shaped horizontal frame member hanging beneath the draw bar head and yieldably supporting the secondary coupling head, a horizontal shank 120 connected to the coupling head, bearings for said shank whereby it may have longitudinal reciprocal movement, means for yieldably maintaining the shank and secondary coupling head in longitudinal alinement, a 125 guide finger projecting from one side of the secondary coupling head face and having upper and lower converging faces, a guide groove formed upon the opposite side of the secondary coupling head and receiving a 130

- complementary guide finger and whereby abutting secondary coupling heads may be brought into alignment, guide arms extending outwardly and over said grooves and a 5 locking recess near the base of said arms for receiving the end of a complementary guide finger and locking the abutting coupler heads in aligned relation to each other, and a plurality of vertically aligned conduit

10 terminals formed in the end faces of the secondary coupling heads and adapted to be held in intimate contact with each other when the heads are locked together.

EUGENE L. HORTON.
